CLAIM

The ornamental design for a cam for a gun cabinet lock, as shown and described.

DESCRIPTION

FIG. 1 is a left front perspective view of a cam for a gun cabinet lock in accordance with the present invention;

FIG. 2 is a front elevation view of the cam for a gun cabinet lock of FIG. 1;

FIG. 3 is a back elevation view of the cam for a gun cabinet lock of FIG. 1;

FIG. 4 is a top view of the cam for a gun cabinet lock of FIG. 1;

FIG. 5 is a bottom view of the cam for a gun cabinet lock of FIG. 1;

FIG. 6 is a left side elevation view of the cam for a gun cabinet lock of FIG. 1;

FIG. 7 is a right side elevation view of the cam for a gun cabinet lock of FIG. 1; and,

FIG. 8 is a left front perspective view of the cam for a gun cabinet lock of FIG. 1 installed in a gun cabinet.

The broken lines in the drawings depict portions of the cam for a gun cabinet lock or the environment in which the cam may be located that form no part of the claimed design.

1 Claim, 4 Drawing Sheets
